LATH BREAKER

Clarence E. Parker, Painesville, Ohio, assignor to
 The Coe Manufacturing Company, Painesville,
 Ohio, a corporation of Ohio

Application January 21, 1942, Serial No. 427,609

8 Claims. (Cl. 164—84.5)

The present invention relates to the manufacture of wallboard for building construction, etc., of the type commercially known as "plasterboard" or "gypsum lath," and similar material.

More particularly, the invention relates to apparatus for mechanically breaking relatively long lengths of plasterboard into more conveniently handled shorter pieces.

Commercial plasterboard of the character referred to comprises a gypsum composition core interposed between relatively thin facing sheets, usually paper, sometimes referred to as "liners." The gypsum composition from which the core of the plasterboard is made is formed into sheets while plastic and the facing material or sheets applied thereto in machines well-known in the art, commonly referred to as "plasterboard machines." After being formed and while still wet, the plasterboard is delivered in suitable lengths to drying apparatus, usually comprising a plurality of conveyors arranged at different levels each adapted to receive one or more plasterboards and carry them through a drying chamber.

For reasons unnecessary to enumerate here, the plasterboard is ordinarily delivered to the dryer in relatively long lengths, usually 12' lengths, and subsequently to drying broken into more conveniently handled shorter lengths, usually 4' lengths. It is common practice to perforate the facing material or liners at the places where it is desired to ultimately break the relatively long lengths of plasterboard and to manually break the plasterboard at the perforations upon its delivery from the dryer.

The principal object of the present invention is the provision of novel apparatus for automatically breaking relatively long lengths of plasterboard and the like into more conveniently handled shorter pieces.

Another object of the invention is the provision of a novel machine adapted to be located adjacent the outfeed end of a multiple deck dryer or the like for breaking relatively long lengths of dry plasterboard into more conveniently handled shorter pieces.

The present invention resides in certain details of construction and combinations and arrangements of parts and further objects and advantages thereof will be apparent to those skilled in the art from the following description of the preferred embodiment described with reference to the accompanying drawings, forming a part of this specification, in which similar reference

characters designate corresponding parts, and in which:

Fig. 1 is a side elevational view of an apparatus embodying the present invention; and

Fig. 2 is a sectional view approximately on the line 2—2 of Fig. 1.

The invention is particularly adapted for breaking plasterboard having transversely extending weakened portions and is herein shown and described as embodied in apparatus designed for that purpose, but it is to be understood that the invention may be employed to break material other than plasterboard. Accordingly, there is no intention herein to limit the invention to the particular embodiment disclosed, but, on the other hand, it is my intention to cover all adaptations, modifications, alternate constructions and uses which come within the practice of those skilled in the art to which it pertains.

Referring to the drawings, the reference character A designates generally a breaking machine embodying the present invention located at the outfeed end of a commercial multiple deck roller dryer B, only a portion of which is shown in the drawings. The number of decks in the breaker A is the same as the number of decks in the dryer. Since the decks are all duplicates in construction, only one deck is herein shown and described in detail.

As the plasterboard C, which, in the embodiment shown, consists of 12' lengths, $\frac{5}{16}$ " to $\frac{3}{8}$ " thick and 16" wide, weakened every 4' by a series of transversely extending perforations 9, emerges from one of the decks of the dryer B it passes

into the horizontally aligned decks of the breaker A. The plasterboard first passes over the driven bottom roll 10 and then between the two driven rolls 11 and 12, one located above and the other below the path of travel of the plasterboard.

From the rolls 11 and 12, the plasterboard travels over a plurality of driven bottom rolls 13, 14, 15, 16, 17 and 18, located comparatively close together and each roll a little higher than the preceding roll. The bottom roll 11 is in line with the bottom roll 10 and spaced therefrom a short distance while the bottom roll 13 is relatively close to but slightly higher than the roll 11. The rolls 11 to 18, inclusive, in effect form an upwardly inclined path with respect to the substantially horizontal path formed by the rolls of the dryer deck and the rolls 10 to 12.

Continued movement of the plasterboard C through the breaker causes it to pass successively spaced alternately arranged top and bottom driven rolls 19, 20, 21, 22 and 23. The bottom

rolls 20 and 22 are in line and slightly above the bottom roll 18, previously referred to. The top rolls 19, 21 and 23 are also in line and form with the bottom rolls a substantially horizontal path through which the plasterboard travels. From the rolls 19 to 23, inclusive, the plasterboard passes between a pair of vertically aligned rolls 24 and 25, the bottom roll 24 of which is driven. In the embodiment shown, the rolls are all approximately 3" in diameter. The rolls 10 and 11 are approximately 8" apart and the rolls 11, 13, 14, 15, 16, 17 and 18 are approximately 4" apart. The roll 20 is about 7½" from the roll 18, and the rolls 20, 22, and 24 are about 12" apart. The top rolls 19, 21, and 23 are located approximately midway between the rolls 18, 20, 20, 22, and 22, 23, respectively. As shown the roll 23 is slightly closer to the roll 22 than the roll 24. The path formed by the rolls 19 to 25 is approximately 4" higher than the path formed by the rolls 10 to 12. The construction is such that as the plasterboard travels over the bottom rolls 10, 11, 13 to 18, and 20, 22 and 24 and underneath the top or hold-down rolls 12, 19, 21 and 23, it is flexed first in one direction and then in another enough to create a tension great enough to break the paper facings and the core of the board when the paper facings are perforated without otherwise damaging the board. The plasterboard is bent through an angle approximately 5 to 12° since the distance between rolls 12 and 20 is about 31½ inches and the distance between rolls 12 and 19 about 28 inches. Because the distance between the weakened transverse line is approximately 4 feet, the fact that the roll 19 is intermediate the rolls 18 and 20 and the further fact that there are no top rolls between the rolls 12 and 19, the bending or deflection is distributed throughout the plasterboard and the angle through which the board is bent varies slightly. The plasterboard C is shown broken at 9' in the drawings.

The rolls are supported in a suitable frame, designated generally by the reference character D, and may be driven in any conventional manner. As shown the roll 10 is driven through the medium of a sprocket chain 26 from the exit roll 27 of the dryer B and each of the bottom rolls 11, 13, 14, 15, 16, 17, 18, 20, 22 and 24 are driven from the preceding roll by means of sprocket chains 28, 29, 30, 31, 32, 33, 34, 35, 36, and 37 operatively connecting the same. The top or hold-down roll 12 is driven from the bottom roll 11 through the medium of star gears 40 connected to the respective rolls and the top rolls 19, 21 and 23 are driven from the roll 12 by sprocket chains 41, 42 and 43 operatively connecting the same. The construction shown is such that the rolls of the breaker are all driven in timed relation to the rolls of the dryer but it will be apparent that any suitable arrangement for driving the rolls may be employed in place of that shown. As shown the lower rolls 10, 11, 13 to 18, 20, 22 and 24 are rotatably supported by suitable bearing members bolted to side members 44 of the frame proper.

In order that lengths of plasterboard may be passed through the breaker without being broken if desired, provision is made for raising the top or hold-down rolls 12, 19, 21 and 23, thus enlarging the pass through which the plasterboard moves so that it will not be flexed and broken in its travel through the machine. For this purpose the top roll 12 is rotatably supported in the ends of levers 47 located at opposite sides of the machine and pivotally connected to the frame proper by bolts 48. The levers 47 are adapted to

be rotated about their pivots to raise and lower the roll 12 by vertically movable members 50 to which they are operatively connected by bolts 51. The lower ends of the members 50 are operatively connected to cranks 52 carried by a horizontal shaft 53 rotatably supported in the frame proper and adapted to be rotated in a clockwise direction, as viewed in Fig. 1, to raise the roll 12 by a foot treadle 54. A link 55, the lower end of which is pivotally connected to the foot treadle 54 and the upper end of which is adapted to engage a fixed stop 56 provides means for holding the foot treadle and in turn the roll 12 in its raised position. The roll 12 is normally held in its "down" position by gravity, the weight being sufficient to flex and break the plasterboard at the perforations 9. A slot 57 in the member 50 where the bolt 51 projects therethrough permits a slight movement of the rolls 12 independent of each other.

The top or hold-down rolls 19, 21 and 23 are carried by members 60 located at opposite ends thereof, which members are pivotally connected to the frame proper by bolts 61 located to the left of the roll 23, see Fig. 1. The members 60 are pivotally connected to vertically movable members 62 by bolts 63 spaced a considerable distance from the bolts or pivots 61. The lower ends of the vertically movable members 62 are connected to bearing boxes 64 which engage about eccentrics 65 on a horizontal shaft 66 rotatably supported in suitable bearings on the frame proper and adapted to be rotated to raise and lower the members 60 and in turn the top rolls 19, 21 and 23 by a crank 67 attached thereto. The top roll 25 is rotatably supported in levers 70 pivotally connected to the frame proper by bolts 71 in such a manner that the roll is free to swing about a horizontal axis and thus merely rest upon the upper surface of the plasterboard without exerting any considerable pressure other than its weight thereon.

As shown in the drawings the breaker A discharges the plasterboard onto a multiple deck discharge table or rack E from which it is removed manually. Alternatively the plasterboard may be discharged onto a suitable conveyor or the like. The discharge table or rack E forms no part of the present invention and is neither shown nor described in detail. Suffice it to say that it comprises table tops or shelves 72 supported by a suitable frame 73 and located slightly below the decks of the breaker A, so that more than one plasterboard can be discharged thereon before it is necessary to remove the same. Preferably the distance from a deck of the breaker A down to the corresponding shelf is from 4 to 6", or enough to hold up 7 or 8 plasterboards before the discharging boards push the one already discharged off the rack E.

The preferred embodiment of the invention has been herein shown and described in considerable detail, but it is not the intention to be limited to the particular construction shown which can be varied within the scope of this invention. For example, the paths between the top and bottom rolls may be widened so as to permit passage of plasterboard therethrough without breaking the same by dropping the lower rolls instead of raising the top rolls as shown. Alternatively this feature of the apparatus may be omitted altogether if desired. In like manner, alternative drives may be employed for the rolls and within certain limits a different arrangement of rolls or guiding means for the plasterboard may be em-

ployed. Other alternative constructions, such as variations in the size and location of the rolls for accommodating plasterboard of a different size than that shown, etc., will readily suggest themselves to those familiar with the art to which the present invention relates.

Having thus described my invention, what I claim is:

1. In an apparatus for automatically breaking plasterboard weakened along spaced predetermined transverse lines, means for engaging opposite sides of the plasterboard to be broken and for moving it forward, said means forming for the plasterboard a path comprising three continuous sections the contiguous sections of which are angularly disposed with respect to each other in opposite directions at an angle of approximately 5° to 12° whereby the plasterboard as it moves therethrough is flexed first in one direction and then in the other, said flexing being sufficient to break the plasterboard at the weakened lines without otherwise damaging the same.

2. In an apparatus for automatically breaking plasterboard weakened along spaced predetermined transverse lines, a plurality of rolls for engaging opposite sides of the plasterboard to be broken and for moving it forward, said rolls forming for the plasterboard a path comprising three continuous sections the adjoining sections of which are angularly disposed with respect to each other in opposite directions at an angle of approximately 5° to 12° whereby the plasterboard as it moves therethrough is flexed first in one direction and then in the other, said flexing being sufficient to break the plasterboard at the weakened lines without otherwise damaging the same, and means for driving a plurality of said rolls.

3. In an apparatus for automatically breaking plasterboard weakened along spaced predetermined transverse lines, a plurality of rolls for engaging opposite sides of the plasterboard to be broken and for moving it forward, said rolls forming for the plasterboard a path comprising three continuous sections the adjoining sections of which are angularly disposed with respect to each other in opposite directions at an angle of approximately 5° to 12° whereby the plasterboard as it moves therethrough is flexed first in one direction and then in the other, said flexing being sufficient to break the plasterboard at the weakened lines without otherwise damaging the same, means for driving a plurality of said rolls, means for supporting a plurality of said rolls for movement transversely of the plane of movement of the plasterboard, and means for moving said last-mentioned rolls transversely of the path of movement of the plasterboard whereby the plasterboard may be passed through the apparatus without being flexed.

4. In an apparatus for automatically breaking plasterboard weakened along spaced predetermined transverse lines, a plurality of rolls for engaging opposite sides of the plasterboard to be broken and for moving it forward, said rolls forming for the plasterboard a path comprising three continuous sections the adjoining sections of which are angularly disposed with respect to each other in opposite directions at an angle of approximately 8° whereby the plasterboard as it moves therethrough is flexed first in one direction and then in the other sufficient to break the plasterboard at the weakened lines without otherwise damaging the same, means for driving a plurality of said rolls, means for supporting a plurality of said rolls located at one side of

the path of the plasterboard for movement transversely of the plane of movement of the plasterboard, and means for moving said last-mentioned rolls transversely of the path of movement of the plasterboard whereby the plasterboard may be passed through the apparatus without being flexed.

5. In an apparatus for automatically breaking plasterboard weakened along spaced predetermined transverse lines, means for engaging opposite sides of the plasterboard to be broken and for moving it forward, said means forming for the plasterboard a path comprising three continuous sections the center one of which has a length approximately one-half of the distance between the weakened lines of the plasterboard and the contiguous sections of which are angularly disposed with respect to each other in opposite directions at an angle of approximately 5° to 12° whereby the plasterboard as it moves therethrough is flexed first in one direction and then in the other sufficient to break the plasterboard at the weakened lines without otherwise damaging the same.

6. In an apparatus for automatically breaking plasterboard weakened along spaced predetermined transverse lines, a plurality of rolls for engaging opposite sides of the plasterboard to be broken and for moving it forward, said rolls forming for the plasterboard a path comprising three continuous sections the center one of which has a length approximately one-half of the distance between the weakened lines of the plasterboard and the adjoining sections of which are angularly disposed with respect to each other in opposite directions at an angle of approximately 5° to 12° whereby the plasterboard as it moves therethrough is flexed first in one direction and then in the other sufficient to break the plasterboard at the weakened lines without otherwise damaging the same, and means for driving a plurality of said rolls.

7. In an apparatus for automatically breaking plasterboard weakened along spaced predetermined transverse lines, a plurality of rolls for engaging opposite sides of the plasterboard to be broken and for moving it forward, said rolls forming for the plasterboard a path comprising three continuous sections the center one of which has a length approximately one-half of the distance between the weakened lines of the plasterboard and the adjoining sections of which are angularly disposed with respect to each other in opposite directions at an angle of approximately 8° whereby the plasterboard as it moves therethrough is flexed first in one direction and then in the other sufficient to break the plasterboard at the weakened lines without otherwise damaging the same, means for driving a plurality of said rolls, means for supporting a plurality of said rolls for movement transversely of the plane of movement of the plasterboard, and means for moving said last-mentioned rolls transversely of the path of movement of the plasterboard whereby the plasterboard may be passed through the apparatus without being flexed.

8. In an apparatus for automatically breaking plasterboard weakened along spaced predetermined transverse lines, a plurality of bottom rolls for supporting the plasterboard to be broken, means for driving a plurality of said bottom rolls, said rolls forming for the plasterboard a path comprising three continuous sections the center one of which has a length approximately one-half of the distance between the weakened lines

of the plasterboard and the adjoining sections of which are oppositely disposed with respect to each other at an angle of approximately 8° , top rolls located at the intersections of said sections, means for driving said top rolls, means located above the third of said sections to be traversed by the plasterboard for engaging the upper surface of the plasterboard, means for supporting

5 said top rolls for movement transversely of the path of movement of the plasterboard, and means for moving said top rolls in a direction away from said bottom rolls whereby plasterboard may be passed between said top and bottom rolls without being flexed.

CLARENCE E. PARKER.
